UNITED STATES PATENT OFFICE.

HERMAN L. HARTENSTEIN, OF CHICAGO, ILLINOIS.

GRAPHOPHONE-CLOCK.

1,104,260.

Specification of Letters Patent. Patented July 21, 1914.

Application filed July 19, 1909. Serial No. 508,424.

To all whom it may concern:

Be it known that I, HERMAN L. HARTENSTEIN, a citizen of the United States, residing at Chicago, in the county of Cook and State 5 of Illinois, have invented certain new and useful Improvements in Graphophone-Clocks, of which the following is a specification.

This invention relates to improvements in 10 combined clocks and talking machines and has for one of its objects the provision of improved means associated with the clock mechanism for intermittently releasing or operating the talking mechanism, whereby 15 the hour and fractions thereof or any other information may be automatically announced.

A further object is to provide improved 20 means whereby the record will receive a definite and uniform degree of movement at each operation of the mechanism.

A further object is to provide improved 25 means whereby the talking mechanism may be readily detached from the clock mechanism, the record readily removed, and a record containing any selection substituted, and the mechanism operated without interfering with or stopping the operation of the clock.

To the attainment of these ends and the 30 accomplishment of other new and useful objects as will appear the invention consists in the features of novelty in the construction, combination and arrangement of the several parts hereinafter more fully described and 35 claimed and shown in the accompanying drawings illustrating an exemplification of the invention, and in which—

Figure 1 is a front elevation, partly in section and with parts broken away, of a clock 40 having an improved attachment constructed in accordance with the principles of this invention applied thereto. Fig. 2 is a longitudinal sectional view on line 2—2 of Fig. 1. Fig. 3 is a transverse sectional view on line 45 3—3 of Fig. 2. Fig. 4 is a sectional view on line 4—4 of Fig. 6. Fig. 5 is a sectional view on line 5—5 of Fig. 3, also showing some of the parts in adjusted position. Fig. 6 is a sectional view on line 6—6 of Fig. 4. 50 Fig. 7 is a modified form of the tripping or releasing mechanism for the talking mechanism. Fig. 8 is a sectional view on line 8—8 of Fig. 7. Fig. 9 is a sectional view on line 55 9—9 of Fig. 7. Fig. 10 is still another modified form of the stop mechanism for the motor. Fig. 11 is a detail sectional view on

line 11—11 of Fig. 3, looking in the direction of the arrows.

Referring more particularly to the drawings, the numeral 15 designates a casing within which the talking mechanism is arranged, and 16 designates a clock case supported by the casing 15 and which contains the clock works.

Arranged within the casing 15 is a support 65 17 which may be secured in position in any desired or suitable manner and mounted upon the support 17 is a talking machine designated generally by the reference numeral 18 in Fig. 2. This talking machine is 70 provided with the usual support 19 for the record 20 which in the present exemplification of the invention is shown in the form of a cylinder and is adapted to be readily removed and replaced upon the support 19 75 in the ordinary and usual manner. The support upon which the record 20 is mounted is provided with a gear 21 with which gears 22 mesh and one of these gears is secured to the feed screw 23. The record support is provided with a pulley 24 by means of which the support and record may be rotated. Motion is imparted to the support 80 from the motor 25 which operates a shaft 26 and a pulley 27 secured to the shaft. A belt 85 28 is provided which connects the pulley 27 with the pulley 24 so that when the motor shaft 26 is operated, motion will be imparted to the record in the ordinary manner. The pulley 27 is provided with a projecting hub 90 29 which may be of any desired length and this hub is provided with a grooved periphery in the form of a spiral thread and rotates when the shaft 26 rotates.

Mounted upon a suitable support 31 which 95 latter is preferably secured to the support 17 is an arm 32 which is provided with a depending projection or extension 33. The arm 32 projects across the drum 29 and the projection 33 thereof is adapted to enter the 100 grooves formed by the threads 30 and is adapted to be shifted laterally as the drum rotates so that when the projection 33 reaches the end of the groove, the drum and shaft 26 will be stopped. In order to accomplish this result the arm 32 is supported for lateral movement upon the support 31 and is provided with a sleeve 34 extending transversely of one end thereof, and through which sleeve the support 31 loosely passes. 105 An elastic member 35, such as a coil spring or the like, is provided which surrounds the

support 31 and is disposed between one end of the sleeve 34 and a stop 36 so that when the arm 32 is being advanced in one direction by the drum 29, the elastic member will be compressed and will remain compressed until the arm 32 is raised to rock the latter about its support 31 to permit the shaft 26 and drum 29 to rotate. When the arm is thus raised, the tension of the elastic member 35 will automatically shift the arm toward the front end of the drum and when the arm reaches this end, it is automatically lowered so that the projection 33 thereon will enter the groove at the front end to be again advanced by the rotation of the drum.

In order to elevate the arm 32, there is provided a shaft 37, upon which is mounted a double cam 38 (shown more clearly in Fig. 6). This shaft 37 is journaled in suitable bearings 39 which latter are preferably secured to the support 17. Secured to the shaft 37 is a gear 40 which in turn meshes with a gear 41 on a shaft 42 mounted in suitable bearings 43 so that when the shaft 42 is rotated, motion will be imparted to the shaft 37 to rotate the cam 38 and to raise the arm 32.

In order to hold the arm 32 elevated so that the projection 33 will not enter the groove on the drum 29 as the arm is shifted under the influence of the elastic member 35, the cam 38 is provided with extended edges upon which the arm 32 rests during the movement of the latter toward the forward end of the drum and by the time the arm has reached the limit of its movement in this direction, the cam 38 will assume a position to permit the projection 33 to drop into the groove of the threads 30 on the drum.

The shaft 42 may be intermittently rotated from the clock works in any desired or suitable manner but is preferably connected so that the spring which operates the striking mechanism will impart movement to the shaft and for this purpose the shaft 42 may be provided with a gear 44, preferably in the form of a sprocket which is secured to one end thereof and over which a flexible member 45, such as a sprocket chain or the like, passes. (See Fig. 1.) This flexible member 45 also passes over a sprocket on the shaft 46 which is journaled in a suitable bearing supported by the casing 15 preferably adjacent the top thereof and in proximity to the clock works. This shaft 46 extends into the casing 16, as shown more clearly in Fig. 2, and is provided with another sprocket wheel 47. The shaft 46 receives its movement from the controller wheel 48, which latter is operated by the ordinary spring which imparts movement to the controller wheel in all clock mechanisms and this controller wheel meshes with a suitable gear 49 on a shaft 50 to which shaft is secured a sprocket wheel 51 and a flexible

member 52, such as a sprocket chain, is provided which passes over the sprockets 46, 51, so that when the controller wheel 48 is released, the spring 53 will rotate the same to impart motion to the shaft 42 through the medium of the connecting sprocket wheels and chains. The usual detent 54 is provided for controlling the movement of the wheel 48 and the wheel is provided with a series of uniformly spaced stop notches 55 in the periphery, which notches are of a uniform depth so that each time the detent 54 is released and operated, the controller wheel 48 will have a uniform or definite degree of movement so that the record 20 will also have a uniform and definite degree of movement during each operation.

Any suitable means may be provided for tripping the detent 54 at regular or predetermined intervals and for this purpose the arbor shaft 56 to which the minute hand is connected is provided with a cam 57 (see Fig. 1), which cam is adapted to engage and rock a pendent 58 to which is secured an arm 59 and which latter is adapted to be moved into engagement with the detent 54 to raise the latter when the cam 57 on the arbor shaft rocks the pendent. It will thus be seen that as the minute hand reaches a predetermined point, the cam 57 will automatically shift the detent 54 to release the controller wheel 48 and when thus released the drum 29 and consequently the motor 25 will be released by the raising and shifting of the arm 32. When the arm 32 is first moved out of engagement with the drum 29, the motor 25 will start to rotate the shaft 26 and the drum 29 and consequently the record 20 so that by the time the arm 32 reaches the limit of its movement under the influence of the spring 35 and the cam 38 has assumed a position to permit the projection 33 on the arm to enter the groove 30 on the drum, the record will have started to move and when the arm reaches the limit of its movement under the influence of its drum 29, the motor 25 as well as the record 20 will be stopped.

The reproducer 59 is supported upon a carriage 60 (see Figs. 3 and 5), which latter moves on the usual guide 61 and is provided with the usual arm or projection 62 co-operating with the worm or screw shaft 23 by means of which the reproducer is advanced intermittently in one direction when the shaft 23 is rotated under the influence of the gears 22 in the usual manner. This arm 62 is adapted to be moved out of engagement with the shaft 23 together with the stylus or needle 63, which latter is moved out of engagement with the record 20 in the ordinary and usual manner, that is, by means of a lever 64 and when the stylus and arm 62 are thus shifted, the reproducer may

be returned to its original or starting position in any desired or suitable manner, but in the present exemplification of the invention, it is returned through the medium of a weight 65, which latter is connected to a flexible member 66, which in turn passes over a suitable pulley 67 and is connected to the reproducer carriage as at 68. The limit of the movement of the reproducer carriage under the influence of the weight 65, which latter is located and moves within a compartment 69 in the base of the casing 15, is controlled by means of a stop 70, supported by a rod or member 71, which latter passes through a suitable collar or portion 72 of the reproducer carriage, and this rod 71 is adjustably mounted in a suitable bearing as at 73 by means of which the position of the stop 70 may be varied.

In order to automatically shift the arm 62 and stylus 63 out of operative position when the latter has reached the end of the record 20, there is provided a support 74, (see Figs. 3, 5 and 11) which is pivotally mounted to any suitable support, preferably to the guide 61 of the reproducer carriage. Secured to this support 74 is a guide 75, secured to which and projecting beyond the ends thereof are members 76, 77. These members 76, 77, are spaced from the support 74 and one of the members, preferably the member 76, is provided with an inclined or beveled extremity 78. The guide 75 and members 76, 77 are so located that when the carriage 60 is moving from the position shown in Fig. 3 toward the right, the lever 64 will project under the guide to hold the stylus in operative position with respect to the record. The extremity of the member 76 terminates at a point so that when the carriage reaches the limit of its movement in one direction, the lever 64 will pass from under the member 76 and over an elastic member 79 in the form of a spring which is so arranged that when the lever 64 passes out of engagement with the member 76, it will raise the lever 64 to move the arm 62 out of engagement with the screw shaft 23 and to raise the stylus. As the lever 64 is raised under the influence of the spring 79, the weight 65 will draw the carriage and reproducer toward the opposite end of the record, causing the end of the lever 64 to ride up the inclined extremity 78 of the member 76 to a position on top of the guide 75, where it will be held until the carriage and reproducer reaches the limit of its movement in the opposite direction. As the carriage reaches the limit of its movement in this direction, the lever 64 will pass off of the member 77 and under an elastic member 80 such as a spring or the like, which latter forces the lever downwardly to a position that when the carriage and reproducer are advanced under the in-

fluence of the screw or worm shaft 23, the lever will pass under the guide 75 to hold the parts in operative position. In order to permit ready access to the reproducer so that it may be shifted from any position after it has started to advance, the support 74 is pivotally mounted, as set forth, and is adapted to be raised by the operator for this purpose, access being had to the support preferably through a suitable opening 76 having a closure 81 in the front of the casing 15. The support may be held in an operative position in any desired or suitable manner, preferably by means of an extension 82 thereon, which enters an opening in a support 83 and the opening and projection are of such dimensions with respect to each other that the projection will have frictional engagement with the support 83 to lock the support 74 against accidental displacement.

Any suitable means may be provided for holding the support 74 elevated to permit the adjustment of the reproducer and for this purpose an elastic member 84, such as a spring or the like, may be provided, one extremity of which is secured to the support 74 and the other extremity is provided with a shoulder or offset portion 85 adapted to engage over the end of the support 83 when the support 74 is elevated, as shown more clearly in Fig. 5.

The tubular member 86 which is connected to the reproducer 59 is adapted to connect with a tubular member 87 preferably located in the compartment 69 in the base of the casing 16 and which latter has communication with an opening 88 extending through the front wall of the casing 15 (see Fig. 2).

In order to use the talking mechanism independently of the clock mechanism, suitable mechanism is provided for disconnecting the clock mechanism therefrom and for this purpose a lever 89 is provided which is preferably fulcrumed intermediate its ends, as at 90, to a suitable support 91 located within the casing 15, shown more clearly in Figs. 2 and 4. One extremity of this lever projects through the casing 115 and is adapted to coöperate with a suitable rack 92 for locking the lever in any of its adjusted positions. Connected to the other extremity of the lever is a laterally projecting arm 93, which extends below the arm 32 and is of a length to engage the arm 32 in any position of the latter. When the lever 89 is depressed, the arm 93 will be raised to engage the arm 32 to raise the projection 33 out of engagement with the 120 grooves and the drum 29 and by locking the lever 89 the arm 32 will be held in its raised position so as to permit the talking mechanism to freely operate, the records being removed and replaced in the ordinary and 130

well known manner. When the lever 89 is released, the arm 93 may be returned by means of a suitable elastic member 94 provided for this purpose.

5 In the exemplification of the invention shown in Figs. 7, 8 and 9, the controller wheel 48 and detent 54 are dispensed with, together with the connecting sprocket chains 45, 52, and coöperating sprocket wheels 44, 10 and the arm 95 is raised directly by the cam 57 on the arbor shaft 56. In order to accomplish this result, there is provided a lever 96 which is pivoted intermediate its ends as at 97 to a suitable support. One 15 end 98 of the lever 96 is deflected laterally and projects under the arm 95. The other end of the lever is connected to an arm 99 of the detent 100 by means of a member 101 which is preferably sectional in construction and provided with a turn buckle 102 for adjustably connecting the sections. With this construction and when the arbor shaft is rotated, the cam 57 will rock the detent 100 and will raise the arm 95 to 20 permit the latter to be automatically adjusted by the spring 103 in a manner similar to the manner in which the arm 32 is adjusted by the elastic member 35. A support 103^a is provided which has a laterally 25 projecting portion 104 for receiving the extremity of the arm 95 when the latter is raised so that the projection 95^a on the arm will be held out of engagement with the drum 29 as the arm moves under the influence of the elastic member 103.

In the form of the invention shown in Fig. 10, the member 101 is connected to an arm 105, which latter is fulcrumed as at 106 intermediate its ends. The free extremity 107 of the arm 105 is provided with a downwardly opening notch or recess 108 adapted to pass over a pin or projection 109 on a gear 110, which latter meshes with a gear 111 secured to the pulley 27. In this 40 form of the invention when the arm 105 is rocked, the gear 110 will be released and as the shaft 26 rotates, the gear 110 will be rotated and will continue until the pin 109 assumes a position to permit the notch 108 in the end 107 of the arm to 45 pass thereover to stop the gear 110 and consequently the shaft 26. With this improved construction, it will be apparent that as the record will have a definite degree of movement each time the mechanism 50 is operated, it will be possible to properly reset the reproducer with respect to the record so as to announce the proper time whenever the clock is set after having 55 been stopped accidentally. Furthermore, the record may be properly divided into uniform spaces to contain the information to be announced at each operation of the mechanism without wasting or losing any 60 space on the record.

Obviously the talking mechanism may be placed within the casing in any desired or suitable position and when once placed in position, access may be had thereto through openings in the walls of the casing 15 which 70 openings may be closed by suitable closures 112.

In order that the invention might be fully understood, the details of the foregoing embodiments thereof have been thus specifically described, but 75

What is claimed as new is—

1. The combination of a clock striking train, a talking machine, mechanism operatively connecting the two, means controlled by the clock mechanism for controlling the operation of the talking machine and means to lock the talking machine out of connection with the striking train whereby it may be independently operated. 80

2. The combination with a clock striking train, a sound producing machine including a record, means for operating the record, means for controlling the operation of the record, including means for rendering the talking machine inoperative and for permitting a uniform and definite degree of movement of the record at each operation thereof, means operated at predetermined intervals by the clock movement for automatically operating the said controlling mechanism, and manual means independent of the clock striking train and the last said means for operating the said controlling means. 90

3. The combination with a clock striking train, a sound producing machine including a record, means for operating the record, means for controlling the operation of the record, including means for rendering the talking machine inoperative and for permitting a uniform and definite degree of movement of the record at each operation thereof, means operated at predetermined intervals by the clock movement for automatically operating the said controlling mechanism, and means independent of the said train for operating the said controlling means and for locking the same to permit the talking machine to operate independently of the clock. 100

4. The combination with a sound producing machine including a record, means for imparting motion to the record, stop mechanism for the record, releasing mechanism for the stop mechanism, a clock striking train associated with said machine, means operated at predetermined intervals by the said train for tripping the said stop mechanism, and means other than the last said means for rendering the stop mechanism inactive to permit the sound producing machine to operate independently of the clock. 110

5. In combination with a clock striking train, a talking machine including a record, 115

means for moving the record, controlling mechanism for the record including a rotatable member operatively related to the record, a pivotally supported member 5 adapted to engage the said rotatable member to stop the record, means operated periodically by the said train for tripping said pivoted member to release the record, and means under the control of the operator 10 for shifting and holding said pivoted member out of operative position whereby the talking machine may operate independently of the clock mechanism.

6. In combination with a clock striking 15 train, a talking machine including a record, a motor for moving the record, a rotatable member operatively related to the motor, a pivoted member coöperating with the rotatable member to stop the record, means 20 whereby the pivoted member will be shifted by the rotatable member to permit a definite and uniform degree of movement of the record at each operation, and means operatively related to said train for automatically 25 shifting said pivoted member to release the record.

7. In combination with a clock striking train, a talking machine including a record, a motor for moving the record, a rotatable 30 member operatively related to the motor, a pivoted member coöperating with the rotatable member to stop the record, means whereby the pivoted member will be shifted by the rotatable member to permit a definite 35 and uniform degree of movement of the record at each operation, means operatively related to said train for automatically shifting said pivoted member to release the record, and means under the control of the 40 operator for shifting and holding said pivoted member out of operative position with respect to the rotatable member.

8. In combination with a clock striking 45 train, a talking machine including a record, a motor for moving the record, a rotatable member operatively related to the motor, a pivoted member coöperating with the rotatable member to stop the record, means whereby the pivoted member will be shifted 50 by the rotatable member to permit a definite and uniform degree of movement of the record at each operation, and means periodically operated by the said train for shifting said pivoted member to release the record.

55 9. In combination with a clock striking train, a talking machine including a record, a motor for moving the record, a rotatable member operatively related to the motor, a pivoted member coöperating with the rotatable 60 member to stop the record, means whereby the pivoted member will be shifted in one direction by the rotatable member to permit a definite and uniform degree of movement of the record at each operation 65 thereof, means operatively related to said

train for automatically tripping said pivoted member to release the record and means for returning the shiftable one of the said rotatable and pivoted members when the pivoted member is tripped. 70

10. In combination with a clock striking train, a talking machine including a record, a motor for moving the record, a rotatable member operatively related to the motor, a pivoted member coöperating with the rotatable member to stop the record, means whereby the pivoted member will be shifted in one direction by the rotatable member to permit a definite and uniform degree of movement of the record at each operation 75 thereof, means operatively related to said train for automatically tripping said pivoted member to release the record, and means for returning the shiftable one of the said rotatable and pivoted members when the pivoted member is tripped, said tripping means also serving to hold the members separated during such return movement. 80

11. In combination with a clock striking 85 train, a talking machine including a record, a motor for moving the record, a rotatable member operatively related to the motor, a pivoted member coöperating with the rotatable member to stop the record, means whereby the pivoted member will be shifted 90 in one direction by the rotatable member to permit a definite and uniform degree of movement to the record at each operation thereof, means operatively related to said train for automatically tripping said pivoted member to release the record, and elastic means for returning the shiftable one of the said rotatable and pivoted members 95 when the pivoted member is tripped. 100

12. In combination with a clock striking 105 train, a talking machine, rotatable member operatively related to the talking machine and provided with a spiral thread on its periphery, a bodily movable and pivotally supported member provided with a portion 110 adapted to coöperate with the thread to be advanced to the end of the thread to stop the record, and means operatively related to said train for automatically moving said member out of engagement with the thread. 115

13. In combination with a clock striking train, a talking machine, a rotatable member operatively related to the talking machine and provided with a spiral thread on its periphery, a bodily movable and pivotally supported member provided with a portion 120 adapted to coöperate with the thread to be advanced to the end of the thread to stop the record, means operatively related to said train for automatically moving said member out of engagement with the thread, and means for automatically shifting the said member to a position to engage the other end of the thread. 125

14. In combination with a clock striking 130

train, a talking machine, a rotatable member operatively related to the talking machine and provided with a spiral thread on its periphery, a bodily movable and pivotally supported member provided with a portion adapted to coöperate with the thread to be advanced to the end of the thread to stop the record, means operatively related to said train for automatically moving said member out of engagement with the thread, means for automatically tripping said pivoted member to move the same out of engagement with the thread, and means for returning the member toward the other end of the thread, said tripping means also serving to hold the member out of engagement with the thread during its said return movement.

15. In combination with a clock striking train, a talking machine, a rotatable member operatively related to the talking machine and provided with a spiral thread on its periphery, a bodily movable and pivotally supported member coöoperating with the thread, elastic means tending normally to move said member toward one end of the thread, said member being adapted to be advanced by the thread to the other end thereof and against the tension of the elastic member to stop the record, and means operatively related to said train for automatically tripping the pivoted member to permit the elastic member to return the pivoted member to the other end of the thread.

30 16. In combination with a clock striking train, a talking machine, a rotatable member operatively related to the talking machine and provided with a spiral thread on its periphery, a bodily movable and pivotally supported member coöoperating with the thread, elastic means tending normally to move said member toward one end of the thread, said member being adapted to be advanced by the thread to the other end thereof and against the tension of the elastic member to stop the record, means operatively related to said train for automatically tripping the pivoted member to permit the elastic member to return the pivoted member to the other end of the thread, and additional means for tripping said pivoted member.

35 17. In combination with a clock striking train, a talking machine, a rotatable member operatively related to the talking machine and provided with a spiral thread on its periphery, a bodily movable and pivotally supported member coöoperating with the thread, elastic means tending normally to move said member toward one end of the thread, said member being adapted to be advanced by the thread to the other end thereof and against the tension of the elastic member to stop the record, and means operatively related to said train for automatically tripping

40 45 50 55 60 65 70 75 80 85 90 95 100 105 110 115 120 125

ping the pivoted member to permit the elastic member to return the pivoted member to the other end of the thread, said tripping means also serving to hold the pivoted member out of operative position with respect to the rotatable member during its return movement.

18. In combination with a clock striking train, a talking machine, a rotatable member operatively related to the talking machine and provided with a spiral thread on its periphery, a bodily movable and pivotally supported member coöoperating with the thread, elastic means tending normally to move said member toward one end of the thread, said member being adapted to be advanced by the thread to the other end thereof and against the tension of the elastic member to stop the record, and means operatively related to said train for automatically tripping the pivoted member to permit the elastic member to return the pivoted member to the other end of the thread, said tripping means including a member having an extended face adapted to engage the pivoted member to release the latter and to hold said member out of operative position with respect to the rotatable member during the said return movement.

19. In combination with a clock striking train, a talking machine, a rotatable member operatively related to the talking machine and provided with a spiral thread on its periphery, a pivotally supported and bodily movable member coöoperating with the thread, means tending normally to move the said pivoted member toward one end of the thread, said member being adapted to be advanced by the thread to the other end thereof and against the tension of the last said means to stop the record, a pivotally supported member adapted to be moved about its pivot to engage and trip the first said pivoted member to release the record, and means controlled by the said train for moving the second said pivoted member.

20. In combination with a clock striking train, a talking machine, a rotatable member operatively related to the talking machine and provided with a spiral thread on its periphery, a pivotally supported and bodily movable member coöoperating with the thread, means tending normally to move the said pivoted member toward one end of the thread, said member being adapted to be advanced by the thread to the other end thereof and against the tension of the last said means to stop the record, a pivotally supported member adapted to be moved about its pivot to engage and trip the first said pivoted member to release the record, means controlled by the said train for moving the second said pivoted member, and additional means for moving the first said

pivoted member into inoperative position and holding the same in such position with respect to the said rotary member.

21. In combination with a clock striking train, a talking machine, a rotatable member operatively related to the talking machine and provided with a spiral thread on its periphery, a pivotally supported and bodily movable member coöperating with the thread, means tending normally to move the said pivoted member toward one end of the thread, said member being adapted to be advanced by the thread to the other end thereof and against the tension of the last said means to stop the record, a pivotally supported member adapted to be moved about its pivot to engage and trip the first said pivoted member to release the record, means controlled by the said train for moving the second said pivoted member, the last said means including a controller wheel having uniformly spaced stops, a detent adapted to coöperate with the stops, and a cam operatively related to the minute hand arbor for tripping the detent.

22. In combination with a clock striking train, a talking machine, a rotatable member operatively related to the talking machine and provided with a spiral thread on its periphery, a pivotally supported and bodily movable member coöperating with the thread, means tending normally to move the said pivoted member toward one end of the thread, said member being adapted to be advanced by the thread to the other end thereof and against the tension of the last said means to stop the record, a pivotally

supported member adapted to be moved about its pivot to engage and trip the first said pivoted member to release the record, means controlled by the said train for moving the second said pivoted member, the second said pivoted member having an extended bearing face for holding the first said pivoted member in operative position with respect to the rotatable member during the said return movement.

23. In combination with a clock striking train, a talking machine including a record, means for controlling the movement of the record comprising a rotatable member operatively connected with the record, said member being provided with a stop, a pivotally supported member adapted to engage the stop for stopping the record, whereby the record will always move a definite and uniform degree, whenever released, means for tripping said pivoted member to release the record, means operated at predetermined intervals by the said train for automatically operating the last said means, additional means under the control of the operator for rendering said stop mechanism inactive whereby the talking machine may be operated independently of the clock mechanism.

In testimony whereof I have signed my name to this specification, in the presence of two subscribing witnesses, on this 16th day of July, A. D. 1909.

HERMAN L. HARTENSTEIN.
